UNITED STATES PATENT OFFICE.

ROBERT McLAUGHLIN AND WILLIAM McLAUGHLIN, OF PHILADELPHIA,
PENNSYLVANIA.

STEAM STOP-VALVE.

SPECIFICATION forming part of Letters Patent No. 571,010, dated November 10, 1896.

Application filed July 9, 1896. Serial No. 598,571. (No model.)

To all whom it may concern:

Be it known that we, ROBERT McLAUGHLIN and WILLIAM McLAUGHLIN, of the city and county of Philadelphia, in the State of Pennsylvania, have invented a certain new and useful Improvement in Steam Stop-Valves, of which improvement the following is a specification.

The object of our invention is to provide simple, efficient, and reliable means for effecting, at a point more or less remote from a valve controlling the delivery of steam from a boiler to an engine or other medium of utilization, the instantaneous closure of said valve upon such sudden and abnormal reduction of pressure in the delivery-pipe leading therefrom as would be caused by the escape of steam in considerable volume upon a rupture of the pipe or its connections, or by a sudden and material release of load or resistance in the operation of an engine supplied with steam by said pipe.

The improvement claimed is hereinafter fully set forth.

The essential features of our invention, generally stated, consist in a piston which is connected to a stop or throttle valve governing a steam-supply pipe leading from a steam-boiler to an engine, a steam heating apparatus or other medium or means for the utilization of steam, and which is normally subject to pressure by which it is maintained in position to hold or to permit the valve to remain open during normal conditions of operation, but upon a release of such pressure, or, equivalently, upon the application of greater opposing pressure, the valve is instantly, directly, and positively closed by an opposing pressure applied either on the opposite side 40 of said piston or to a connected piston in oppositely-acting direction, as the case may be. The release of the pressure upon the piston by which the valve is held open, or the application of greater opposing pressure, is effected either manually or automatically; in the former case by the opening of an outlet or valve by an operator, which outlet or valve may be one of a number located at different, desired, and determined points more or less 50 remote from the stop-valve, whereupon the pressure on the opposite side of the piston

moves it into position in which it closes the connected stop-valve. Automatic release of pressure upon a piston by which a stop-valve is held open is effected by the sudden and material reduction of pressure in the steam-supply pipe on the delivery side of the valve, (from which portion of the pipe the steam which acts on the piston is taken,) caused by unduly sudden release of load of the engine, 55 whereupon higher boiler-pressure, acting upon a second piston of smaller diameter connected to the stop-valve in opposite direction to the piston by which the valve is held open, closes said valve.

In order to prevent injury to an operator by the escape of steam from the outlet through which pressure is relieved from a piston to close the stop-valve, which outlet may be afforded by breaking a frangible tube or plate or displacing a detachable plug provided for the purpose, such tube, plate, or plug is inclosed in a pressure-tight safety-box having a pipe leading to a proper point of discharge, and any desired number of such safety-boxes or of pressure-release valves may be employed, being located at points where they may be readily accessible and be operated without exposure to escaping steam from a rupture of the steam-pipe, which would render the 80 stop-valve inaccessible. The improvement thus constitutes an effective safety appliance in preventing loss of life or severe injury to engineers and firemen or others employed in the fire-room of a steam vessel or other closed boiler-compartment, by enabling the escape of steam from a ruptured steam-pipe to be instantly stopped by the actuation of a simple and positively-acting device at any one of a number of points located in such 85 positions and at such distance from the stop-valve and steam-pipe as to be accessible without contact with or injury from the escaping steam.

Our improvement is readily applicable to 95 stop-valves of the ordinary pattern without involving any material alteration thereof, and may also be applied for closing the main injection-valves or other sea-valves of steam vessels.

In the accompanying drawings, Figure 1 is a diagrammatic vertical longitudinal section

through a steam vessel illustrating an application of our invention; Fig. 2, a similar transverse section; Fig. 3, a similar section through a building, showing our invention applied in connection with the boilers thereof; Fig. 4, a vertical central section through a steam stop-valve embodying our invention; Fig. 5, a similar section taken at a right angle to Fig. 4; Fig. 6, a view, partly in elevation and partly in section, of a safety-box; Fig. 7, a similar view of a steam stop-valve illustrating a structural modification of our invention; Fig. 8, a similar view of the same, taken at a right angle to Fig. 7; Fig. 9, a vertical central section through a stop-valve, illustrating a further structural modification; Fig. 10, a view, partly in elevation and partly in section, of the same, taken at a right angle to Fig. 9; Fig. 11 a front view in elevation of the safety-box of Fig. 10; Fig. 12, a front view in elevation, illustrating a modified form of safety-box; Fig. 13, a longitudinal central section through the same; Fig. 14, a view, partly in elevation and partly in section, of a portion of a steam-pipe, illustrating the application of our invention with the employment of two pistons; Fig. 15, a transverse section through the same, and Fig. 16 a side view in elevation of a steam-engine with the device of Figs. 14 and 15 applied on its steam-pipe.

Referring first to Figs. 4, 5, and 6, our invention is shown as applied in connection with a steam stop-valve, which, in and of itself, is substantially of the ordinary standard form, and is of the type known as a "non-return" valve, the valve proper being held in open position by the pressure of the steam in the boiler and closing by its own gravity when the pressure therein falls to or near that of the atmosphere. The globular body 1 of the valve is provided with inlet and outlet passages 2 3, having suitable flanges for connection to a boiler and to a steam-pipe, respectively, and is closed at top by a cap 4, having a central stuffing-box 5. Communication between the inlet and outlet passages 2 and 3 is controlled by a lift or puppet valve 6, which seats on a ring or bushing 7 at the inner end of the inlet-passage 2, and which is connected, by a screw-cap 8, to a central stem 9, having handles 10 on its outer end. Except when held down to its seat by the screwed stem and nut hereinafter described, the valve 6 may be raised therefrom by the stem 9 or by steam-pressure in the inlet-passage 2. Two parallel columns 11 11 are screwed into the body 1 and cap 4, and are connected at top by a yoke 12, which is held in position by nuts 13, engaging threads on the upper or outer ends of the columns. For convenience of construction the collars 14, against which the yoke bears, are made separate from the columns, which are slightly reduced in diameter at and adjacent to their outer ends to receive and hold the collars against shoulders.

A cylinder or pressure-chamber 15, having a circumferential flange 16 on its outer end and provided with a head 17 of substantially similar diameter to the flange 16, is fitted to slide longitudinally on the columns 11, the flange 16 and head 17 being recessed to fit thereon, as indicated by dotted lines in Fig. 4. The inner end of the cylinder 15 is closed and provided with a central tubular extension 18, which passes through the stuffing-box 5 of the valve-body and is made of such length that when the cylinder 15 is brought to its lowest or innermost position the tubular extension will abut against the screw-cap 8 of the valve 6 and hold the latter against its seat 7. The cylinder 15 is fitted with a properly-packed piston 19, the diameter of which is greater than that of the valve 6, and to which is fixed a tubular piston-rod 20, which passes through the tubular extension 18 and surrounds the stem 9 of the valve. The inner end of the piston-rod 20 is adapted to abut against the cap 8 of the valve, and it is made of such length that when the piston is depressed to the inner extremity of its traverse in the cylinder the piston-rod will force the valve 6 to and hold it on its seat.

The cylinder 15 may be raised and lowered and held in any determined position on the columns 11 in order to hold the valve 6 closed when required or to limit, as desired, the maximum elevation of the valve from its seat. For this purpose the head 17, which is bolted to the cylinder, is provided with a tubular stem 21, which surrounds the valve-stem 9 and is externally screw-threaded, its thread engaging a nut 22, which is fitted to rotate in the yoke 12 and is connected to a hand-wheel 23. By rotation of the hand-wheel in one or the other direction the cylinder may be raised or lowered, as desired, and is held in adjusted position by the engagement of the stem 21 and nut 22.

The piston 19 is normally held at the outer extremity of its traverse in the cylinder by being subjected when in such position to the pressure of steam from the boiler upon a greater area on its inner than on its outer side. The piston is made a differential one, in this instance, by forming a projecting ring 24 on its outer face, which ring is finished and fits truly against a corresponding finished annular face 25 on the inner side of the head 17. Pressure on the outer side of the piston therefore acts only on the smaller annular surface thereof surrounding the ring 24 when the piston is at the outer extremity of its traverse, while pressure on the inner side of the piston acts upon the materially larger area surrounding the tubular piston-rod 20. We do not, however, limit ourselves to a differential piston of the above specific construction, and hereinafter describe another form by which the same result is equivalently attained.

Steam from the boiler is supplied to the cylinder 15 on opposite sides of its piston 19

by a pipe or pipes 26, a single pipe with proper connections being in this case employed, and communication with the cylinder being effected through telescoping pipes in order to admit of the longitudinal movement of the cylinder on the columns without permitting the escape of steam. The pipe 26 leads into a chamber 27, formed in the yoke 12, and a pipe 28, fixed to the cylinder-head 17 and passing through a stuffing-box into the chamber 27, supplies steam to the cylinder on the outer side of the piston 19. A similar chamber 29 is fixed to the cap 4 of the valve-body, and a pipe 30, fixed to the inner end of the cylinder 15, passes through a stuffing-box into the chamber 29. The pipes 28 and 30 telescope into and out of the chambers 27 and 29 in the movements of the cylinder and thus maintain communication between the same and the chambers irrespective of the position or condition of movement or rest of the cylinder.

The chamber 29 may communicate either directly or indirectly with the pipe 26 or communicate directly with the boiler by an independent pipe, as preferred. In the instance shown in Fig. 5 a branch pipe 31 is lead from the boiler-supply pipe 26 into a chamber 33, in the lower part of which it opens by a contracted nozzle 32. A partition 34, in which are formed openings or perforations having an aggregate transverse area substantially equal to or somewhat greater than that of the pipe 30, is fixed in the chamber 33 above the nozzle 32, and a pipe 35 is led from the chamber 33 above the partition 34 to the chamber 29. Steam from the boiler passes through the pipes 26 and 28 to the outer side of the piston 19 and through the pipes 26 and 31, chamber 33, and pipes 35 and 30 to the inner side of said piston, a free discharge being admitted from the inner side, when required, by the perforations in the partition 34.

The release of pressure from the inner or lower side of the piston 19 is effected, whenever the closure of the valve 6 is desired to be made by said piston, by opening an outlet from a release-pressure pipe 36, communicating with the chamber 33 and through said chamber and the pipes 35 and 30 with the cylinder 15 on the inner side of the piston 19. The release-pressure pipe 36 is led to any desired point or points (which may be more or less remote from the stop-valve) at which it may be deemed advisable or necessary to provide means for closing the stop-valve, and at each of said points it communicates with a discharge-pipe 37, leading to the atmosphere, to the condenser, or to any other safe and convenient point of discharge. The release-pressure pipe and discharge-pipe communicate either through a connecting-pipe 38, governed by a release-valve 39, or through a normally-closed passage having a frangible or detachable member 40, which may be a glass tube, as shown in Figs. 5 and 6, a disk, as shown in Fig. 10, or a detachable plug, as

shown in Fig. 13. Both of these pressure-varying or releasing devices, that is to say, a valve-governed pipe and a pipe having a frangible or detachable member, may be applied at each point of desired actuation, the special object of the latter device being to provide a means of release which can be actuated with quickness and certainty by unskilled persons, who in an emergency might not be able to properly operate a valve. The frangible or detachable member 40 is preferably inclosed in a pressure-tight safety-box 41 in order to prevent the operator from being scalded by the escaping steam, and is broken or detached, as the case may be, by striking a slight blow upon a head 42, fixed upon a pin 43, the opposite end of which abuts against the frangible or detachable member 40. Upon the breakage or detachment of said member an outlet is immediately opened, through which pressure on the inner side of the piston 19 is released through the pipes 36 and 37 and their connections, and the pressure on the outer side of the piston thereupon depresses said piston and closes the valve 6.

As shown in Figs. 1 and 2, the pressure-varying or releasing devices may be located in various positions in a steam vessel, as in the engine-room, fire-room, pilot-house, and different points on the several decks. Fig. 3 shows the releasing devices in the engine-room, fire-room, and each of the different stories of a building. It will also be seen from these figures that by connecting the pressure-release pipes of the stop-valves of a battery or set of boilers the simultaneous closure of the stop-valves of all the boilers will be effected.

The construction shown in Figs. 7 and 8 operates similarly to that shown in Figs. 4, 5, and 6, and above described, and differs therefrom only in the form of the differential piston 19, which in this case is that of a frustum of a cone, the pressure-chamber, which corresponds, in function and relation to other members, with the cylinder 15, before described, corresponding in form with the piston. The piston 19 is provided with expansible packing-rings 45, which fit in circumferential grooves in the piston, and are maintained in contact with the surface of the pressure-chamber by steam, which is admitted behind them from the space above the piston through passages 44, leading into the packing-ring grooves. By the contact of the expansible packing-rings 45 with the pressure-chamber, which is thus maintained in all positions of the piston, it is made differential, and, as in the instance first described, subjected, when in normal position, to pressure upon a larger area on its inner than on its outer side. The pipe connections employed in this construction may be similar to those shown in Fig. 5, and before described.

In the modification shown in Figs. 9 and 10 the piston 19 is, as in the preceding instance,

normally subject to an excess of pressure on its inner side, by which it is maintained at the outer limit of its traverse. The inward stroke of the piston, by which the closure of the valve 6 is effected, is, however, in this case produced by the admission of steam to the cylinder 15 on the outer side of the piston, instead of by its release therefrom, as in the preceding instances, and the outward pressure on the piston is afforded by a spring. The cylinder 15 is open at its inner end, and is provided with legs or standards, which are bolted to the cap 4 of the valve-body 1. A short stem 46 is formed on or fixed to the lower side of the valve 6, and moves in a guide 47, fixed in the inlet-passage 2. A piston-rod 48, secured to the piston 19, passes through the stuffing-box 5 of the valve-body, and is connected at its lower end to the valve 6. A helical spring 49, which surrounds the piston-rod 48, abuts against the inner side of the piston 19 and against a stop fixed to the inner end of the cylinder, the tension of said spring being such as to normally hold the piston at the outer limit of its traverse, in which position the connected valve 6 will be fully open. To enable the valve 6 to be closed or its lift limited when and as required, a stem 50 passes through a stuffing-box in the cylinder-head 17 and abuts against the piston when at the outer limit of its traverse, said stem being threaded to engage a nut in the yoke 12, which, in this case, is fixed to the cylinder, and carrying a hand-wheel 51. By the rotation of the hand-wheel the piston and connected valve 6 may be pressed downward until the valve is brought to its seat, or for such shorter distance as will limit the lift of the valve to any desired degree.

The pressure-supply pipe 26 leads from the boiler into the outer end of the cylinder, and a safety-box 40 is interposed between two sections of said pipe. Communication between the sections of pipe on opposite sides of the safety-box is normally cut off by a frangible member 40, which in this instance is in the form of a plate or disk closing a port or passage-way through the safety-box. The plate 40 may be broken by a blow on the head 42 of a pin 43, which passes into the safety-box and abuts against the plate 40. Upon the fracture of the plate 40 steam is admitted to the outer side of the piston 19, and, by its pressure thereon, forces the piston downwardly and seats the connected valve 6, as in the instances before described.

Figs. 12 and 13 show a form of safety-box in which communication is established between the release-pressure pipe 36 and discharge-pipe 37 to release the pressure from the inner side of the piston, in the constructions of Figs. 4, 5, 7, and 8, by displacing a detachable member having the form of a plug 40, which closes the opening of the pipe 36 to the safety-box 41. The plug 40 normally rests on a block 53, which is preferably provided with an elastic bearing, and which may be adjusted to

hold the plug properly in position by a set-screw 54. The detachment of the plug is effected, when immediate closure of the stop-valve is desired, by striking a slight blow on the head 42 of the pin 43, which abuts against the plug 40, and pressure is thereby released from the inner side of the piston through the pipes 36 and 37, as before described.

Figs. 14, 15, and 16 illustrate our invention as applied to effect the closure of a valve 57, controlling the steam-supply pipe 55 of a steam-engine 56, so as to immediately and automatically shut off the supply of steam to the engine in the event of a sudden and abnormal decrease of the load of the latter, and thereby prevent the damage resultant upon the engines "running away," which is liable to occur in such case. The construction will also effect the closure of the valve in the event of the bursting of the steam-pipe on the side of the valve toward the engine. The valve 57, which is of the butterfly type, is journaled transversely to the steam-pipe 55, and a double-armed lever 59 is fixed on the projecting end of one of its journals. A cylinder 15, provided with a piston 19, is journaled to the steam-pipe on one side of the axis of the valve 57, and a cylinder 15^a, of smaller diameter and fitted with a piston 19^a, is journaled to the steam-pipe on the opposite side of the axis of the valve. The piston-rod 48 of the cylinder 15 is coupled to one of the arms of the lever 59, and the piston-rod 48^a of the smaller cylinder 15^a is coupled to the other arm of said lever. Steam from the boiler is supplied to the cylinder 15^a by a pipe 26, and the cylinder 15 is connected by a pipe 58 with the steam-pipe 55 at a point near the engine. The pipes 26 and 58 are made sufficiently flexible or are so-jointed as to permit of the vibration of the cylinders 15 and 15^a upon their pivots or trunnions, when required, without leakage of steam.

The pressure of the steam upon the piston 19 of the cylinder 15 is normally greater than that upon the piston of the cylinder 15^a, owing to the larger area of the former, and forces the piston 19 to the outer limit of its traverse, in which position it holds the connected valve 57 open and permits a free flow of steam through the pipe 55 to the engine. When, however, the pressure in the steam-pipe on the side of the valve nearer to the engine is suddenly and materially reduced, as by an abnormal increase in the speed of the engine or by the bursting of the pipe, the then greater pressure in the pipe 26, acting on the piston 19^a of the cylinder 15^a, moves said piston outwardly against the diminished resistance of the pressure on the piston 19 and immediately closes the valve 57, shutting off the supply of steam to the engine or to the ruptured portion of the steam-pipe, as the case may be.

We claim as our invention and desire to secure by Letters Patent—

1. The combination of a valve for controlling the flow of fluid through a pipe, two pis-

tons which are normally and coincidently subject to pressure upon unequal areas respectively, rods connected to said pistons and adapted to impart the differential pressures acting thereon, in opposite directions, to said valve, and means for applying a preponderance of pressure to the smaller piston area.

2. The combination of a valve for controlling the flow of fluid through a pipe, a piston which is normally subject to unequal pressures on opposite sides, a rod connected to said piston and adapted to impart pressure to said valve, a normally-closed pipe through which a variation of the degree of pressure on one side of said piston may be effected, and a frangible or detachable member for opening communication through said pipe.

3. The combination of a valve for controlling the flow of fluid through a pipe, a piston which is normally subject to unequal pressures on opposite sides, a rod connected to said piston and adapted to impart pressure to said valve, a normally-closed pipe through which a variation of pressure on one side of said piston may be effected, a frangible or detachable member for opening communication through said pipe, and a pressure-tight safety-box inclosing said frangible or detachable member.

30 4. The combination of a valve for controlling the flow of fluid through a pipe, a piston which is normally subject to unequal pressures on opposite sides, a rod connected to said piston and adapted to impart pressure to said valve, a normally-closed pipe through which a variation of the degree of pressure on

one side of said piston may be effected, and a series of frangible or detachable members for opening communication through said pipe at any one of a number of points variously located relatively to the valve.

5. The combination of a valve for controlling the flow of fluid through a pipe, a differential-piston mechanism, which normally permits the valve to remain open, and means for effecting the closure of the valve by said differential-piston mechanism by changing the direction of preponderance of pressure thereon.

6. The combination of a valve for controlling the flow of fluid through a pipe, a cylinder or pressure-chamber fitted to traverse toward and from said valve on guides on the body or casing thereof, a differential piston fitting said pressure-chamber and held normally by pressure therein in position to permit the valve to be open, a rod on said differential piston extending into the valve-body and adapted to impart pressure to the valve, pipes for the supply of fluid under pressure to opposite sides of said differential piston, and means for releasing pressure from the larger area of said differential piston.
